LIPSTICK HOLDER

Girolamo Piccoli, Croton-on-the-Hudson, N. Y., assignor to Fabergé, Inc., New York, N. Y., a corporation of New York

Application October 12, 1949, Serial No. 5,438

Term of patent 14 years

(Cl. D86—10)

To all whom it may concern:

Be it known that I, Girolamo Piccoli, a citizen of the United States, residing at Brook Trail, Croton-on-the-Hudson, in the county of Westchester and State of New York, have invented a new, original, and ornamental Design for Lipstick Holder, of which the following is a specification, reference being had to the accompanying drawing, forming a part hereof, in which:

Fig. 1 is a top plan view of a lipstick holder, embodying the new design,

Fig. 2 is a front elevational view of the holder, and

Fig. 3 is a side elevational view of the holder.

I claim:

The ornamental design for a lipstick holder, as shown.

GIROLAMO PICCOLI.
